United States Patent Office

Des. 202,223
Patented Sept. 7, 1965

202,223

DECANTER AND CLOSURE THEREFOR

Ernest L. Du Pree, New York, N.Y., assignor to Schenley
Industries, Inc., New York, N.Y., a corporation of
Delaware

Filed July 14, 1964, Ser. No. 80,861

Term of patent 14 years

(Cl. D58—8)

Fig. 2

Fig. 5

Fig. 6

FIGURE 1 is a side elevational view of a decanter and closure therefor embodying my new design;

FIGURE 2 is a sectional view, taken on the line 2—2 of FIGURE 1;

FIGURE 3 is a sectional view, taken on the line 3—3 of FIGURE 1;

FIGURE 4 is a sectional view, taken on the line 4—4 of FIGURE 1;

FIGURE 5 is a sectional view, taken on the line 4—4 of FIGURE 1; and

FIGURE 6 is a top plan view thereof.

I claim:

The ornamental design for a decanter and closure
